DIE

William J. Sullivan, St. Louis, Mo., assignor to
Independent Die and Supply Company, St.
Louis, Mo., a corporation of Missouri

Application August 13, 1936, Serial No. 95,828

8 Claims. (Cl. 164—93)

This invention relates generally to dies and particularly to dies of the perforating type such as those generally employed in the manufacture of shoes having perforated designs therein.

- 5 Dies of the kind referred to have, as a general rule, been made as a composite article, a separate complete die being provided for each different shape of perforated design. In a few instances, however, such dies have been arranged to receive 10
- 10 a variety of cutting elements so that by the exchange of a few parts the die might be converted so as to accomplish different perforated designs.

The object of the present invention generally stated is to provide a die of the kind referred to 15 constructed and arranged so that the parts thereof may be readily exchanged so as to convert the die and adapt it to perform different perforating operations.

20 A further object of the present invention is to provide a die of the kind referred to wherein the conventional stripper plate may be lifted or removed with facility.

25 Another object of the present invention is to provide a die of the kind referred to with a gauging device and means for holding such gauging device in association with the die whereby it may be readily removed and exchanged.

30 Other objects will become apparent to those skilled in the art when the following description is read in connection with the accompanying drawings in which:

Figure 1 is a plan view of a die constructed in accordance with the present invention.

35 Figure 2 is a perspective view of the die shown in Figure 1 with the stripper plate thereof lifted.

Figure 3 is a sectional view taken along line 3—3 of Figure 1 showing the arrangement of the stripper plate, its holding device and the cutting element.

40 Figure 4 is a sectional view taken along line 4—4 of Figure 1.

Figure 5 is a sectional view taken along line 5—5 of Figure 1.

45 In accordance with the present invention a die of the perforating type is provided with a base upon which may be mounted a cutting element and a stripper plate for cooperating with the cutting element. The present invention particularly contemplates that the cutting element as well 50 as its cooperating stripper plate may be readily removed from the base so as to permit exchange of these parts for similar parts adapted to perforate different designs. In accordance with the present invention the cutting element of the die is constructed and arranged so as to be securely

held in position during operation of the device and the stripper plate is so arranged as to prevent removal of the die without lifting the stripper plate from position. A further feature of the present invention resides in the provision of an exchangeable gauging device for use upon the die so as to adapt the die to perforation of a variety of sizes or shapes of shoe parts in which the same perforated design may be desired.

55 Referring now to the drawings, for an illustrative embodiment of the present invention the die may comprise a base 1 upon which is mounted a cutting element 2. In the embodiment shown the cutting element comprises a plurality of perforating tubes 3 in the center of which is a lozenge shaped cutter 4. In the embodiment shown the cutting element 2 is held upon a pad 5 which latter is secured to base 1. Pad 5 may be provided with a plurality of studs arranged to receive clamps 6 and nuts 7. The nuts 7 may be knurled 10 or otherwise provided for convenient manipulation. With the arrangement just described and particularly if the clamps 6 are formed of spring metal and so shaped as to resist tightening of nuts 7 when the jaw parts 8 thereof are disposed 15 over the supporting plate of cutting element 2 as shown clearly in Figure 2 it will be understood that upon tightening of nuts 7 cutting element 2 is securely held down against pad 5. In order to prohibit sidewise displacement of cutting 20 element 2 the latter may be provided with two or more apertures such as 9 into which pins extending upwardly from pad 5 may fit. While the arrangement just described securely holds cutting 25 element 2 in the desired position upon pad 5, it 30 will be understood that by merely loosening nuts 7 clamps 6 may be turned so as to release the cutting element and permit replacement thereof by another having apertures positioned as the 35 apertures 9 for use upon the same basic die parts. 40

A stripper plate 10 is also provided for cooperation with the die. In accordance with the usual practice the stripper plate 10 may have a series of openings 11 and 12 therein slightly larger 45 than perforating tubes 3 and cutter 4 respectively. A stripper plate 10 may be mounted so as to yield under pressure and permit openings 11 and 12 to move down over perforating tubes 3 and cutter 4 respectively. In order to accomplish this a series of posts such as 13, 14 and 15 may be mounted upon base 1. Posts 13 and 14 are arranged to provide a hinge connection with stripper plate 10 as clearly shown in Figure 4 while post 15 is arranged to provide a releasable fastening to co- 50 55

operate with a latch 16 upon the bottom of stripper plate 10.

Each of posts 13, 14 and 15 may conveniently be composed of telescoping parts 17 and 18 having flanges 19 and 20 respectively or other suitable means to prevent the inside part 17 from being ejected from the outside telescoping part 18. A spring 21 may then be suitably mounted within telescoping parts 17 and 18 so as to bias these parts into their extended position as shown in Figure 4, but nevertheless to permit movement thereof upon the exertion of pressure downwardly upon stripper plate 10.

As remarked above, post 15 may have its upper portion arranged to cooperate with latch 16 and to this end may be formed with a head 22 having a groove 23 therein for cooperation with latch 16. In the embodiment shown latch 16 comprises a simple spring, one end of which is mounted in a block 24 having an aperture 25 for the reception of head 22. The other end of the spring may be curled as shown in Figure 2 or otherwise arranged for convenient manipulation. When the stripper plate is in its closed position as shown in section 25 in Figure 3, it will be understood that latch 16 fits into groove 23 so as to hold the parts against separation, but by mere flexing of latch 16 the parts are released so that the stripper plate may be lifted on its hinges as shown in Figure 2.

30 A gauging device 26 having a gauging surface 27 may be provided. In accordance with the present invention the gauging device 26 is readily removable and conveniently exchangeable. In order to accomplish this the gauging device 26 35 may be provided with a pair of apertures 28 each arranged to receive and cooperate with posts 29 upstanding from the upper surface of stripper plate 10 in order to prevent lateral displacement of the gauging device upon the stripper plate. 40 In order to maintain the gauging device against removal but yet facilitate its exchange a stud 30 may be provided downwardly extending therefrom for cooperation with aperture 31 in stripper plate 10 and engagement with a spring clasp 32 45 therebeneath so that the spring clasp 32 impossibly holds stud 30 against removal. In the embodiment shown stud 30 is provided with a bulbous end into the recess beyond which the parts of spring clasp 32 may engage, thus holding stud 30 in position. With the parts thus arranged, however, by the exertion of a sufficient force in an upward direction upon gauging device 26 the elements of spring clasp 32 will be cammed outwardly by the bulbous surface of stud 50 30, thus releasing the latter. In order to facilitate the application of such upward pressure upon gauging device 26 the corners thereof may be upset slightly in order to provide lips 33 beneath which the pressure of the fingers may be applied.

60 While in the foregoing description one illustrative embodiment of a die constructed in accordance with the present invention has been disclosed, it will be understood that the several features of the die illustrated in the accompanying drawings may be employed independently of the other features to the end that certain of the parts may be removed or exchanged with facility while other parts may remain a permanent part of the die, it will nevertheless be apparent that 65 with the various parts, including the gauging device, stripper plate and cutting element, arranged and secured in position as shown, a die is provided which may be modified and employed for various perforating operations with a minimum 70 of inconvenience.

It is realized that many modifications in the precise arrangement shown in the accompanying drawings will present themselves to those skilled in the art and it is further realized that various features of the present invention may be advantageously employed independently of other features and consequently it is to be distinctly understood that such modifications and the use of such individual features and subcombinations of features as do not depart from the spirit of this invention 10 are, although not specifically described herein, contemplated by and within the scope of the claims.

Having thus described the invention what is claimed is:

1. A die of the kind described comprising, a base, a cutting element mounted upon the base, compressible posts carried by the base, and a stripper plate hinged to some of said posts and releasably connected to another of said posts. 20

2. A die of the kind described comprising, a base, a cutting element mounted upon the base, compressible posts carried by the base, and a stripper plate hinged to some of said posts and a latch cooperating with another of said posts to 25 connect the stripper plate thereto.

3. A die of the kind described comprising, a base, a cutting element mounted upon the base, compressible posts carried by the base, and a stripper plate hinged to some of said posts and a spring latch cooperating with another of said 30 posts to connect the stripper plate thereto.

4. A die of the kind described comprising, a base, a cutting element mounted upon the base, studs on said base, jaw members on each of said 35 studs having a part engageable with said cutting element, and means for drawing said jaws into engagement with said cutting element to hold the same against the base, compressible posts carried by the base, and a stripper plate hinged 40 to said posts.

5. A die of the kind described comprising, a base, a cutting element mounted upon the base, studs on said base, spring jaw members on each of said studs having a part engageable with said 45 cutting element, and means for drawing said jaws into engagement with said cutting element to hold the same against the base. 50

6. A die of the kind described comprising, a base, a cutting element mounted upon the base, 55 studs on said base, jaw members on each of said studs having a part engageable with said cutting element, and means for drawing said jaws into engagement with said cutting element to hold the same against the base, compressible posts carried by the base, and a stripper plate mounted on said posts, a gauge having a post arranged to cooperate with an aperture in said stripper plate, and a yieldable latch engageable with the end of 60 said post beneath said stripper plate.

7. A die comprising a stripper plate, a gauge plate, one of said plates having a post with a spheroidal end, the other of said plates having an aperture for cooperating with said post and a spring clasp for engaging said spheroidal end when the post is in said aperture. 65

8. A die comprising, a stripper plate, a gauge plate, said plates respectively having cooperating posts and apertures, and resilient means carried 70 by one of said plates for impossibly engaging and latching a post carried by the other plates in position in the corresponding apertures.
